CLAIM

The ornamental design for a collar ornament, substantially as shown and described.

DESCRIPTION

FIG. 1 is a front view of a collar ornament showing my new design.

FIG. 2 is an enlarged sectional view taken along the line 2—2 of FIG. 1.

FIG. 3 is a rear view thereof.

FIG. 4 is a top plan view thereof with portions broken away to reveal interior details.

The broken line showing of a collar in FIG. 1 is for illustrative purposes only and forms no part of the claimed design.
